(57) **CLAIM**

The ornamental design for a pipette, as shown and described.

DESCRIPTION

1. Pipette

1.1 : is a bottom view of a pipette showing my new design;

1.2 : is a front view thereof;

1.3 : is a back view thereof;

1.4 : is a perspective view thereof;

1.5 : is a left view thereof;

1.6 : is a perspective view thereof;

1.7 : is a top view thereof;

1.8 : is a right view thereof; and

1.9 : is an enlarged view thereof.

The portions of the "pipette" shown in broken lines form no part of the claimed design.
